UNITED STATES PATENT OFFICE.

REGINALD A. FESSENDEN, OF WASHINGTON, DISTRICT OF COLUMBIA, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

METHOD OF TRANSMITTING ENERGY BY ELECTROMAGNETIC WAVES.

1,172,017.

Specification of Letters Patent.

Patented Feb. 15, 1916.

Application filed May 12, 1906. Serial No. 316,521.

To all whom it may concern:

Be it known that I, REGINALD A. FESSENDEN, citizen of the United States, and resident of Washington, District of Columbia, 5 have invented certain new and useful Improvements in Methods of Transmitting Energy by Electromagnetic Waves, of which the following is a specification.

The invention herein described relates to 10 the art of transmission of electrical energy, and more particularly to the transmission of energy by electro-magnetic waves, and still more particularly to the transmission of telegraphic or telephonic signals.

15 My invention includes an improved method of signaling by commutating the source of energy, as hereinafter more fully described and claimed.

In the accompanying drawings forming a 20 part of this specification, Figures 1, 2, 3 and 4 show forms of apparatus embodying my invention.

Heretofore in the practice of the art it 25 has been customary to generate such high frequency oscillations as are used for generating electromagnetic waves by means of a spark gap, or a vacuum tube, or a high frequency dynamo. It has been customary to produce an effect at the receiving station 30 by causing the electric oscillations to effect an imperfect contact, or a perfect contact or to rectify the waves by means of a vacuum tube or to produce a direct dynamic action.

35 In the practice of my invention I employ a rapidly revolving commutating device, capable of transforming a continuous current into an alternating current, of high frequency, and also a receiving system capable of rectifying the same by transforming it into a continuous current. In Fig. 1 such a commutating device is shown. The commutator is preferably fixed and has alternate segments 7, 7, 7 connected 40 by wire 7^a, and intervening segments 8, 8, 8 connected together by wire 8^a, while intervening between the segments, are insulating segments 9, 9, 9. If the inside diameter of the commutator be 8 inches and the 45 commutator segments be $\frac{1}{16}$ of an inch wide inclusive of insulation there will be approximately 400 such segments in the circumference. 5 is a revolving brush prefer-

ably flexible at the end and having an adjustable balance weight 6, and revolving at 55 a speed of 500 revolutions per second. 1 is an antenna, 3, 12 and 16 are condensers, preferably adjustable, 4, 10 and 11 are inductances or inductive resistances preferably adjustable, 13, 14 is a source of voltage 60 and 2 is a ground connection. On revolving the brush 5 the antenna 1 is put into contact alternately with one or the other set of commutator segments, and as the middle point 15 of the source of voltage is connected to ground, the aerial 1 is alternately charged above and below the potential of the earth at a frequency of 100,000 alternations per second. In this way electromagnetic waves are generated and can be used 70 for signaling purposes.

Fig. 2 shows a receiving station where the antenna 1 is inductively connected to the commutating device 19 by means of the transformer 17, 18 and the antenna is 75 grounded at 2. 20 is a telephone receiver which is caused to produce signals by the currents rectified or re-transformed by the commutating device 19 being connected, through coil 18, to the brush 5 and by wires 80 37 and 8^a to the segments. As the commutating device 19 revolves at a rate nearer or farther away from synchronism with the transmitting commutator, beats are produced of a lower or higher pitch in the telephone 85 20.

In Fig. 3 is shown a device used for wireless telephony. Here 1 is the antenna grounded at 2, 27 is a telephone transmitter, 22 22' is a transformer, 23 the commutating 90 device, 24 and 25 a battery having its middle point 26 connected to ground as shown.

In Fig. 4 is shown another form of wireless telephone where the antenna 1 is connected to the commutating device 28. 32, 95 33 is the secondary of an induction coil having its middle point 34 grounded at 2. 29 is the primary of an induction coil, 30 a battery and 31 a telephone transmitter. In the operation of this latter device the transmitter 31 on being spoken into produces electric waves of corresponding intensity in the antenna 1, which being received at a receiving station reproduce the speech.

In the design of the commutating device 105 here shown it is preferred that the brushes

should revolve and the commutator be fixed. By this means all difficulties due to great loss of power from wind friction and friction of bearings and from difficulties in constructing a commutator to revolve at such high speeds without flying to pieces or becoming inoperative through unbalancing are overcome.

While only one brush and commutator is shown I do not limit myself to one brush or commutator as various arrangements may be used. Nor do I limit myself to the particular electrical arrangements shown as the invention herein described is widely applicable and may be employed with any of the devices well known in the art.

It is to be noted that a commutator differs from a rectifier in that a commutator is capable of changing a direct current into an alternating current, as well as changing an alternating current into a direct current, whereas a rectifier is only capable of rectifying an alternating current into a direct current. Moreover, a rectifier does not strictly change an alternating current into a direct current, but merely suppresses one-half of the alternating current. By the term "commutating" I will be understood to mean strictly the changing of one kind of current into the other continuously and without loss of energy.

What I claim is:

1. The method of transmitting energy by electro-magnetic waves by mechanically commutating the source of energy at the same frequency as the waves to be produced.

2. The method of transmitting energy by electro-magnetic waves by mechanically communicating a direct current into alternating current, and commutating the resulting alternating current into direct current at the receiving end.

3. In the art of transmitting energy by high frequency electric oscillations, the method comprising producing high frequency currents by mechanically commutating the source, and commutating said currents as received to produce an indication without storing or losing the energy, substantially as described.

4. The method of signaling consisting in generating and receiving electro-magnetic waves by mechanically varying the potential to create oscillations in the sending conductor, and commutating them in the receiving circuit.

5. The method of signaling consisting in mechanically generating oscillations by changing the potential of a sending conductor alternately above and below that of the ground connection at wave frequency, and receiving said oscillations to produce signals by mechanically commutating them in a local circuit connected to a receiving antenna.

6. The method of signaling by electro-magnetic waves which comprises generation of oscillations by commutating a source of direct current at a frequency corresponding to the waves it is desired to produce, receiving said waves on an absorbing antenna, commutating the resulting alternating current therein into direct current and operating an indicator thereby, substantially as described.

7. The method of generating and receiving electro-magnetic waves by mechanically commutating the current at the frequency of the waves.

8. The method of transmitting energy which comprises generating high frequency oscillations by mechanically commutating a source of current at the frequency of the waves it is desired to produce, and receiving said waves by commutating and thereby transforming them into direct current at the receiving station.

9. The method of signaling by electro-magnetic waves which comprises mechanically commutating a source of current to produce the oscillations, and mechanically commutating the resulting alternating current at the receiving station to transform the same and effect a receiving instrument.

10. The method of producing high frequency oscillations by mechanically connecting a radiating circuit alternately with points of different potential in a circuit containing a current source, such commutation being at the frequency of the waves desired to be produced.

11. The method of signaling by electro-magnetic waves which comprises the transforming of direct current into high frequency alternating current by a mechanical commutator at the sending end and transforming the alternating current into direct current by a similar mechanical commutator of approximately the same frequency at the receiving end.

12. In wireless telegraphy, the method of generating current for radiating Hertzian oscillations, which comprises charging the radiating device from a continuous source at separated intervals synchronous with the time period of the oscillations, substantially as described.

13. In wireless telegraphy, the method of generating oscillations by alternately connecting and disconnecting a radiator with a source of potential at a frequency the same as the time period of the oscillations to be generated, substantially as described.

14. Apparatus for transmitting energy by electro-magnetic waves, comprising a mechanical commutator operating to commutate the currents at the same frequency as the waves used in the transmission, substantially as described.

15. Apparatus for transmitting energy by

- electro-magnetic waves, comprising a mechanical commutator at each of two stations, one operating to commute the source of current into high frequency oscillations, and 5 the other operating to commute the resulting alternating current into direct current.
16. A tuned circuit connected with a voltage source, a connection from a point of intermediate voltage in said source to the 10 ground, combined with an antenna and a commutator connecting the same alternately with parts of said circuit of different voltage, substantially as described.
17. A wireless telephone transmitter comprising a source and an antenna, a commutator for connecting the antenna to points in the source having different potentials with frequency high enough to produce electromagnetic waves, and a telephone 15 transmitter in the antenna circuit adapted to modify said stream of waves in accordance with speech.
18. In wireless signaling apparatus, a circuit comprising an inductance and a capacity and having a natural period of oscillation and being adapted to cause radiation of energy at a high oscillation frequency, a source of voltage, and a rotating device connected to alternately charge the capacity in 20 different directions at a rate dependent upon the speed of rotation, substantially as described.
19. Apparatus for transmitting electrical energy comprising a current source and a commutator operating to continuously produce high frequency oscillations therefrom, a receiving circuit including a receiver operable by continuous current and a commutator operating to change the received currents into direct currents, to produce an effect on the receiver, substantially as described.
20. In wireless signaling apparatus, the combination with a current source and an antenna, of a commutator alternately connecting the antenna with points of different voltage on the source at wave frequency.
21. In transmitters for wireless telegraphy, the combination with a sending circuit, of mechanically operated means for positively completing and interrupting said circuit synchronously with the time period of Hertzian oscillations of definite frequency. 50
22. In transmitters for wireless telegraphy, the combination with a sending circuit, of mechanically operated means for positively reversing the current in said circuit synchronously with the time period of Hertzian oscillations of definite frequency. 55
23. In a transmitter for wireless telegraphy, the combination with an oscillatory circuit, of mechanically operated means for positively completing and interrupting said circuit synchronously with its time period 60 of each oscillation.
24. In transmitters for wireless telegraphy, the combination of an oscillatory circuit, a condenser therein, means for supplying current for charging the condenser, 70 and mechanically operated means for positively discharging said condenser synchronously with the time period of each oscillation.
25. In transmitters for wireless telegraphy, the combination with an oscillatory circuit, of a sectional generator wheel, means coöperating with the sections of said wheel to produce oscillations in said oscillatory circuit, and means for rotating said 75 wheel at a definite speed to complete and interrupt said circuit synchronously with the time period of each oscillation.
